DOCKING DEVICE

Hugh F. McClain, Long Beach, Calif.

Application September 10, 1945, Serial No. 615,273

8 Claims. (Cl. 61—67)

1

This invention relates to a device by means of which a ship may be set down on its keel in a dry-dock.

One object of the invention is to provide a device for aligning a vessel in a dry-dock. Another object is to provide means for indicating the horizontal and the vertical position of the keel of a ship being placed on supporting blocks in a dry-dock. Still another object is to provide means for aligning and setting down a ship having a pronounced list. These and other objects are attained by my invention which will be understood from the following description, reference being made to the accompanying drawings which form a part hereof, in which:

Fig. 1 is a diagrammatic top elevational view showing a ship in a dry-dock;

Fig. 2 is a cross-sectional view taken on the line 2—2 of Fig. 1;

Fig. 3 is a front elevational view of the keel-contacting bar device of my invention;

Fig. 4 is a cross-sectional view taken on the line 4—4 of Fig. 3;

Fig. 5 is a cross-sectional view taken on the line 5—5 of Fig. 3;

Fig. 6 is a cross-sectional view taken on the line 6—6 of Fig. 3;

Fig. 7 is a cross-sectional view taken on the line 7—7 of Fig. 6;

Fig. 8 is a wiring diagram of the electrical system of my device.

Fig. 9 is a front elevational view of the annunciator R used in my device.

In general, my invention consists of two sets of locator switches placed above the keel blocks fore and aft with an annunciator mechanism conveniently placed above water on the dock structure, the combination being adapted to give visual signals indicating the lateral and vertical position of the keel at two positions lengthwise of the ship, one fore and the other aft.

In the drawings, Figs. 1 and 2, a dry dock structure D is indicated with a ship S floating in the water, the bottom of the ship being above the supporting blocks B. In the position shown, the ship is about to rest on the blocks, and the keel K is in contact with the upwardly thrust keel-contacting bar 11 of my device. The annunciator R is shown on the dock structure at the side of the ship. In the ordinary method of docking a vessel in a dry dock, the supporting blocks are first positioned on the floor of the dock to correspond with the under-structure of the ship which is to be dry docked. It is, of course, important that the keel of the ship be centered

2

upon the keel blocks, so that the weight of the ship will not distort the structure when the water is removed and the entire weight of the ship is on the supporting blocks. Furthermore, it is desirable to have the ship centered in the dry dock space so that the necessary scaffolding may be erected on either side to facilitate carrying on the repair work. In the docking of war vessels such as cruisers and battleships which have narrow hulls near the keel, it is particularly important to have the keel centered on the keel blocks to avoid damage to the ship's structure.

The usual method of docking a vessel involves much mathematical calculating following the use of surveying instruments placed on the dock structure, and sometimes requires the use of divers to ascertain if the ship is coming down properly on the supporting blocks. By my method, it is unnecessary to survey the vessel with instruments, and it is possible to dock the vessel properly on the keel and other supporting blocks without loss of time and without requiring the services of skilled docking engineers.

In my device, the keel actuates electrical switches on two crosswise keel-contacting bars placed at positions fore and aft, these switches controlling lights or other signals on an annunciator board disposed to correspond to the position of the keel to one side or the other of center line of the keel blocks, and also its position vertically above the top of the keel block. By merely watching the visual signals on the annunciator as the vessel is being let down onto the supporting blocks, it is possible to guide the sidewise movement of the ship, while it is still floating, to the center line position, and thus cause the ship to be supported mainly on its keel.

Referring to the keel-contacting bar shown particularly in Figs. 3 and 4, a crosswise member 12 is attached by pins 13 to upright tubular members 14 slideably mounted in a supporting frame 15 which is attachable to a keel block by bolts in the bolt holes 16. Back teeth 17 are provided in each of the tubular members, arranged to contact with the toothed pinions 18 mounted adjacent the upright tubular members 14 on the shaft 19 so that the cross member 12 may be raised and lowered to parallel positions above the keel block. A coil spring 20 having one end attached at 21 to the shaft 19 and the other end to the frame 15 tends to keep the tubular members and the attached cross-member in its extended position upward to press against the keel of the ship as it approaches the rest position on the supports B in the dry dock. As the ship's keel touches the

contactor bar, it is pushed downwardly but maintains its position parallel to its original position because of the two racks and pinions.

A series of spring switches suitably spaced along the length of the contacting bar are attached thereto with the contacting levers 23 exposed above the top surface of the top cross member 12.

Referring particularly to Fig. 5, one form of spring switch which may be used is shown, with the details of its attachment, in a water-proof conduit welded along the length of the top cross member, with openings 24 covered by plates 25 attached by bolts 26 fastened into the structural member 12. The switch lever 23 is attached to the shaft 27 mounted in the bushing 28 having a bonnet 29 to provide waterproof packing 30 around the shaft. A contacting arm 31 is attached to the shaft 27 by the pin 32, an electrical contacting member 33 being provided on the end of the arm to make electrical contact with the fixed contact point 34. A coil spring 35 around the shaft 27 and abutting the end of the casing insures that the contact is broken when no pressure is applied to the contacting levers 23, and for good electrical contact between the contact points. When the ship's keel touches the contacting lever 23, the shaft 27 is rotated bringing the contacts 33 and 34 together, closing the switch S and the electrical circuit, thus causing a visual signal such as an electric light to show on the annunciator panel indicating the relative position at which the contact was made. When the ship is properly centered, it will ordinarily actuate the two center switches, or corresponding switches on either side of the center.

The vertical distance of the keel above the keel block is indicated on the annunciator by vertically spaced lights controlled by the multipoint switch 37 also mounted in the water-proofed conduit on the cross member 12. The shaft 38 of this switch 37 is connected to the arm 35 and to the frame 15 by the toggle arm 36. The multipoint switch 37 is shown in detail in Fig. 6, the toggle arm 35 turning the shaft 38 mounted in the bushing 39, held by the cover plate structure 40 with bonnet 41 and packing for water proofing 42. A contacting arm 43 is attached to the shaft by the key pin 44 which is provided with a contact member 45 which makes contacts with the contact points 46, 47, 48, and 49, which are so placed relative to the movement of the contactor arm 43 to indicate selected vertical distances above the top of the keel block. As the top cross member 12 is pushed downwardly by the keel K of the ship being docked, the toggle arms 35 and 36 actuate the shaft 38 to move the contact member 45 into electrical contact with one of the fixed contact points 46, 47, 48, or 49. By making these electrical contacts, vertically placed lights, or other signals are actuated on the annunciator R to indicate the elevation of the keel above the keel block.

When a vessel is to be docked which is listing to one side or the other, particularly if the ship has a relatively flat bottom, it is desirable to incline the keel-contacting cross bar with its switches at an angle corresponding to the list angle so that the switches will be contacted by the keel and not by a lower point on the ship's structure due to the listing. The keel-contacting bar may be set at this list angle by raising the rack pins out of contact with the pinion, tilting the bar to the desired inclination and then allowing the racks to engage the teeth of the pinion 75

wheels at the differently extended positions, thus allowing parallel movement of the bar.

As shown in the drawings, two keel contacting switch bars are employed, one fore, and one aft and the annunciator is shown correspondingly to indicate lateral and vertical positions of the keel fore and aft.

The particular switch structures which are here shown are for illustrated purposes only and other types of spring switches having suitably exposed levers may be employed. Equivalent means for parallel movement of the contacting bar may be used instead of the rack and pinion device shown.

The advantages of my invention will be apparent, since its use permits the expeditious docking of ships in dry docks.

I claim:

1. A device for use in guiding the keel of a ship onto the center line of the keel blocks on a dry dock, comprising an electrical switch-controlled annunciator, a keel-contacting bar disposed cross-wise of said dock, a bank of spring switches having exposed switch levers spaced at known intervals along said keel-contacting bar, and means to movably support said bar above the elevation of the top surface of the keel block, said annunciator being controlled by the said switches when the ship's keel contacts the switch levers on said bar as the ship descends toward the keel blocks.

2. A device for use in guiding the keel of a ship onto the center line of the keel blocks on a dry dock, comprising an electrical switch-controlled annunciator, a keel-contacting bar disposed cross-wise of said dock, a bank of spring switches having exposed switch levers spaced at known intervals along said keel-contacting bar, means to movably support said bar above the elevation of the top surface of the keel block, and height-indicating switches operated by said bar at intervals above said keel block top surface, said annunciator being controlled by the said switches when the ship's keel moves said bar and contacts the switch levers on said bar as the ship descends toward the keel blocks.

3. A device for use in guiding the keel of a ship onto the center line of the keel blocks on a dry dock, comprising an electrical switch-controlled annunciator consisting of spaced visual signal means, a keel-contacting bar disposed cross-wise of said dock, a bank of spring switches having exposed switch levers spaced at known intervals along said keel-contacting bar, and means to movably support said bar above the elevation of the top surface of the keel block, said annunciator signals being controlled by the said switches when the ship's keel contacts the switch levers on said bar as the ship descends toward the keel blocks.

4. A device for use in guiding the keel of a ship onto the center line of the keel blocks on a dry dock, comprising an electrical switch-controlled annunciator, a keel-contacting bar disposed cross-wise of said dock and having means for inclining said bar from the horizontal to conform to the list of the ship, a bank of spring switches having exposed switch levers spaced at known intervals along said keel-contacting bar, and means to movably support said bar above the elevation of the top surface of the keel block, said annunciator being controlled by the said switches when the ship's keel contacts the switch levers on said bar as the ship descends toward the keel blocks.

5. A device for use in guiding the keel of a ship

onto the center line of the keel blocks on a dry dock, comprising an electrical switch-controlled annunciator, a keel-contacting bar disposed cross-wise of said dock, a bank of spring switches having exposed switch levers spaced at known intervals along said keel-contacting bar, and rack and pinion means for supporting said bar, spring means adapted to hold said bar against the keel of a ship being docked, said annunciator being controlled by the said switches when the ship's keel contacts said switch levers on said bar as the ship descends toward the keel blocks.

6. A device for use in guiding the keel of a ship onto the center line of the keel blocks on a dry dock, comprising an electrical switch-controlled annunciator consisting of spaced visual signal means, a keel-contacting bar disposed cross-wise of said dock, a bank of spring switches having exposed switch levers spaced at known intervals along said keel-contacting bar, a pair of adjustable upright supports for said bar, means to upwardly thrust said bar against the keel of a ship being docked, and a height-indicating multipoint switch operated by levers connected to said bar actuating spaced signal means in said annunciator, said annunciator signals being controlled by the said switches when the ship's keel moves said bar and contacts said switch levers on said bar as the ship descends toward the keel blocks.

7. A docking instrument for use in guiding the keel of a ship onto the center line of the keel blocks on a dry dock, comprising an electrical

switch-controlled annunciator consisting of visual signal means spaced to correspond to the positions vertically and horizontally of one portion of said keel, a keel-contacting bar disposed cross-wise of said dock, a bank of spring switches having exposed switch levers spaced at known intervals along said keel-contacting bar, double rack and pinion means operatively interconnected adapted to support said bar in parallel elevational positions, spring means to press said bar upwardly against the keel of a ship being docked, and a height-indicating multipoint switch operated by lever means attached to said keel-contacting bar, said annunciator signals being controlled by the said switches when the ship's keel moves said bar and contacts said switch levers on said bar as the ship descends toward the keel blocks, to show on the annunciator both the height above the keel-block, and the lateral position of the keel relative to the center point of said keel blocks.

8. In a device for use in guiding the keel of a ship onto the center line of the keel blocks on a dry dock, an electrical switch-controlled annunciator, and a bank of spring switches having exposed switch levers spaced at known intervals along a cross-wise keel-contacting bar supported for parallel movement in an up-and-down direction, said annunciator signals being controlled by the closing of one or more switches when in contact with the ship's keel when the ship is descending toward the keel blocks.

HUGH F. McCORMICK.
